UNITED STATES PATENT OFFICE.

LEONARD W. DAVIS, OF HERKIMER, NEW YORK, ASSIGNOR TO LULU DAVIS, OF HERKIMER, NEW YORK.

GAME APPARATUS.

1,110,905.

Specification of Letters Patent. Patented Sept. 15, 1914.

Application filed January 15, 1914. Serial No. 812,192.

To all whom it may concern:

Be it known that I, LEONARD W. DAVIS, a citizen of the United States, residing at Herkimer, in the county of Herkimer and State of New York, have invented certain new and useful Improvements in Game Apparatus, of which the following is a specification, reference being had therein to the accompanying drawing.

10 My invention relates to a game apparatus, and I declare the following to be a full, concise and accurate description thereof, sufficient to enable anyone skilled in the art to which it appertains to make, use and play 15 the same, reference being had to the accompanying drawings in which like reference characters refer to like parts throughout the specification.

The object of the invention is to provide 20 a game apparatus that will be instructive, as well as entertaining. The game will be found to be an excellent mental exercise in figures and a great aid to those persons who desire to become expert accountants or to 25 those who desire to master the rapid mental calculation of figures. The game is designed to represent time in its various divisions and is played on a board made for the purpose. These objects are attained by the 30 device illustrated in the accompanying drawings, in which:

Figure 1 is a plan view of the game; Fig. 2 is a section taken on the line 2—2 of Fig. 1; Fig. 3 is a section taken on the line 3—3 of Fig. 1; Fig. 4 is an enlarged perspective view of a block or cube employed; Fig. 5 is an enlarged perspective view of a member employed.

Referring more particularly to the drawings, the game comprises a board 15, which may be made of wood or other suitable material, having marked thereon a circle 20. Between the circle 20 and the outer edge 21 of the basin 22 which is located in the center of the board 15 there are marked off four spaces 23, 24, 25, and 26, each representing one of the four seasons of the year and limited laterally by the heavy dark diagonal lines, connecting the circles 20 and 21. To more clearly define the spaces 23, 24, 25, and 26 from each other, any given scheme that will produce a striking contrast of colors may be employed, for instance, the space 23, representing spring,

the first season of the year might be colored green, the space 24, representing summer, colored yellow, the space 25, representing fall, colored gray, and the space 26, representing winter, colored white. Furthermore, each of the spaces 23, 24, 25, and 26 is divided into 13 smaller spaces or weeks, which are numbered from —1— to 13 inclusive. There is formed in the center of the larger or season spaces 23, 24, 25, and 26, a small basin 30 adapted for the reception of the four pegs 31 for insertion at the proper intervals to be hereinafter explained in the holes 41 in the board 15 to indicate the number of times the play has gone around the board. The basin 22 is also adapted for the reception of other of the pegs 31 for insertion in the holes 40 to indicate the number of points scored by the individual player. The basins 22 and 30 are constructed by sinking suitable shaped depressions in the board 15, which depressions are lined with aluminum 32.

The rules and manner of playing the game are as follows: Each of the four seasons 23, 24, 25 and 26 is assigned to a player, who is provided with three of the men 33, which are so disposed on the spaces numbered 1 to 13, in the respective season spaces 23, 24, 25 and 26, that when all the twelve men 33 are placed on the board 15, there will be one number numerically that will not be covered. This number that is not covered, or as I choose to term it, the vacant number, is denoted by the block or cube 34, which has the word "Indicator" marked on each of its six sides. It will be observed that the numbers 1 to 13 are marked in the corners of their respective spaces, whereby they may be readily seen even when the men 33 are disposed thereon. The object of the game is to be the first person to secure thirteen pegs, each representing seven days, which pegs are taken from the center basin 22, as they are won and disposed in the holes 40 to the right of the player. The first player may be chosen by the players, but in successive games the next person to the left becomes the first player. Furthermore, when starting the game, the first player takes one of the pegs 31 contained in the small basin 30 in the season space 23 and places the same in the first of the holes 41 immediately in front of his place to indicate that the play

is on the first turn around the board. Assuming that the player assigned to the spring season space 23 is the first to play, he has the privilege of moving anyone of his three men 33 onto the vacant space, or 7, in this instance. He will, therefore, so move, if possible, that the sum of the numbers covered by his men 33, after he has moved, will equal 7 or a multiple of seven, for the player is awarded one peg for every sum that is seven or a multiple thereof. In the illustration shown in the Fig. 1, the player of the spring season 23, would be unable to so move anyone of his men 33 upon the vacant number seven that the sum of the numbers covered by his men 33 after he had moved would equal seven or a multiple thereof. The player would try, therefore, to so move as to prevent his opponent to the left of him from making seven or a multiple thereof. Assuming further that the player of the spring season 23 moves the man 33 now on space 2 to the space of the vacant number 7, for he is obliged to move one man and only one at a time, then the vacant number for the player of the summer season space 24, would be 2, which number would be indicated by disposing the block 34 thereon. The player of the season 24 now moves, if possible, that one of his three men 33 onto the space of the vacant number or 2, which will give him seven or a multiple thereof. He, too, in this instance, is unable to so move that the sum of the numbers covered by his men 33, after he has moved, will equal seven or a multiple thereof. This player, therefore, would try to so move that his opponent to the left of him will be unable to make 7 or a multiple thereof. Assuming that the player of the summer season space 24, moves the man 33 now on 12 to the space of the vacant number 2. The vacant number becomes 12, which will be indicated by the block 34. The third player, or the player of the fall season 25 then plays that one of his three men 33 onto the vacant number 12, that will give him, if possible, the sum of seven or a multiple thereof. He, too, in this instance, will be unable to make the required sum to secure one or more pegs. Assuming that the third player, moves the man 33 on 9 to the space of the vacant number 12. The vacant number is now 9, which is indicated by disposing the block 34 onto that space in the fourth or winter season 26. The fourth player, or player of the winter season, will now move the man 33 on 6 to 9, the vacant number, in order to secure the sum, twenty-one, namely three sevens, which represent twenty-one days, that being the greatest multiple of seven, possible, in this instance. The player, therefore, takes three pegs 31 out of the center basin 22 and disposes them in the holes 40 to his right. As the play now passes again to the first player,

he takes the second one of the four pegs 31 contained in the small basin 30 in his season space 23, and places the same in the second of the four holes 41 immediately in front of the spring season space 23, to indicate that the play is on the second turn around the board. The playing continues as before, the number on the space from which the last player moves his man 33 becoming, in each instance, the vacant number on which the next player to the left must play. The playing now continues under these rules until the fourth time around the board, which is termed Leap Year. During the leap year turn, the first player must use the extra day of that year, if he can move in such a manner, that the sum of the numbers covered by his men 33, will equal 8, 15, 22, 29 or 36, or 1 plus any possible multiple of seven, unless the player should be able so to move as to make seven or its multiple, in which event he may exercise the option. In either case the player is awarded one peg for each seven plus one, or each seven, in accordance with the option exercised, so made. If the extra day is not thus used by the first player, the privilege passes on to the second, who may use it under the same conditions. If not used by the second, it passes to the third, and if not used by the third, the privilege passes to the fourth player, who is obliged to use the extra day in order to count. If the fourth player can not use the extra day, and can move so as to make seven or its multiple, he must so move without counting. The playing continues until one of the players has made the thirteen pegs, without again considering leap year in that game. All four players may continue, even after this, until all but one player has made thirteen pegs, if the players desire to determine the successive order in which they would win the required number of pegs, thirteen.

Since the fifty-two pegs represent only three hundred sixty-four days and there are three hundred sixty-five days in a calendar year, the player to make the last count in a game is governed by the same rules prescribed above for the fourth player in leap year. However, it is not necessary that any of the players make just the exact number of pegs required to finish the game. If he needs one peg only, but can make more than one, he may use the one peg and thereby win the game.

The players may play with individual scores, or they may play as partners, in which event, the opposite players would be so considered. In this instance, when one player has made the required number of pegs, thirteen, he continues playing, but throws his count to his partner. The two players first making twenty-six pegs are to be considered the winners of the game.

The game may be played by two persons

under the same conditions as played by four persons, the only difference being that each of the two persons plays the opposite season spaces and as he finishes each play, he turns 5 the board one quarter way around to bring the next space opposite his opponent.

There is a sufficient number of the pegs 31, fifty-two in all, disposed in the basin 22 at the beginning of the game for use by the 10 players in keeping count of their respective scores. The four other pegs 31, which are employed to keep track of the number of times the play has gone around the board are kept in the basins 30 and are passed to 15 the player at the left at the beginning of each successive game.

The game is called "Zeit" from the German word time because of its proximity thereto, to wit: the game combined represents 20 years (the four larger spaces or divisions 23, 24, 25, and 26, represent the four seasons, the twelve men 33, represent the twelve calendar months, the fifty-two pegs disposed in the center basin 22 at the beginning 25 of the game, for use in keeping track of the individual scores, each represent seven days or a total number of three hundred sixty-four days for each year with one day added to make 365 days and one extra day for leap year, and the smaller spaces or 30 thirteen weeks into which each season space is divided represent the fifty-two weeks in each year.

Having thus described my invention what

I claim as new and desire to secure by Letters Patent is:

1. In a game apparatus, a board, a given figure on said board, said figure comprising an annular space, said annular space being divided into quarters, said quarters being subdivided into thirteen smaller spaces, numbers marked in said spaces, and men for moving about on said spaces, whereby to count seven or a multiple thereof.

2. In a game apparatus, a board, basins in said board for holding pegs, and a given figure on said board, said figure comprising an annular space, said annular space being divided into quarters, said quarters being subdivided into thirteen smaller spaces, numbers marked in said spaces, and men for moving about on said spaces, whereby to count seven or a multiple thereof.

3. In a game apparatus, a board, basins in said board for holding pegs, aluminum lining for said basins, and a given figure on said board, said figure being divided into four spaces, said spaces being further subdivided into smaller spaces, and numbers on said smaller spaces, whereby the combination of said numbers will give the sum of seven or a multiple thereof.

In testimony whereof I have affixed my signature in the presence of two witnesses.

LEONARD W. DAVIS.
